 tion of Illinois

Application March 23, 1951, Serial No. 217,179

10 Claims. (Cl. 1—8.1)

1

The present invention relates to an attachment for standard or conventional types of nailing machines and more particularly to a novel means and manner of accurately aligning a form and the contained component parts of any section to be nailed together, including the forming of the sides, ends or other part of a crate, box, container, etc.

Such standard or conventional nailing machines are of the open back clincher type in which clincher plates are disposed in a slot or elongated opening in the work table of the machine with the slot disposed parallel to the chuck rails and otherwise positioned so that the nails driven will be above the clincher plates. The clincher plates of these standard or conventional nailing machines are separated at their ends by bridges which are disposed in vertical positions across the slot with their ends resting in vertical grooves or recesses in the sides of the slot and their top ledges flush with the top of the work table. When such conventional clincher plates are in inoperative position their top surfaces are sufficiently below the top of the work table to permit the nails to pass through the work and protrude into the slot between the bridges when the heads of the nails are tight against the top surface of the work or sunk below the surface as desired. At the proper moment in the nailing cycle while the nail drivers are still firmly in contact with the nail heads the clincher plates are propelled suddenly upward to a point that their top surfaces are slightly above the top of the work table and thereby the nails are properly clinched. Thereafter the nail drivers and the clincher plates resume their inoperative positions.

One requirement to proper nailing of a section as herein disclosed and composed of several narrow cleats and slats, is to feed the form therefor through the machine with its lateral edges (the edges parallel to the line of travel) so positioned that no nails will impinge on or protrude so near the bridges that they cannot be properly clinched.

The function of the bridges is to support the bottom cleat or slat if it is over and parallel to the slot while the nails are being driven. If the bridges are too far apart the cleat or slat will be bent down against the clincher plates when the nails are driven. The nails would then not protrude through that bottom cleat or slat and when the clincher plates are propelled upward the nails would not clinch but buckle somewhere in their length.

It has been the usual practice for an operator

5 of a nailing machine of the type with which the present invention is employed, to endeavor to visually gauge the position of the form and its crate parts with respect to markings on the form and on a side rail which should register or be in alignment for each nailing stroke.

The conventional method of guiding the forms along their lateral edges is to employ two side rails, gauges or guides which are adjustable in position and between which the forms are pushed or fed. One of these side rails usually does not extend across the front work table thus permitting the forms to be moved onto the table at that end and into position for feeding.

15 This method of using two, side rails is objectionable for the following reasons.

1. Side friction occurs on the forms, thus more energy is required to push the forms through the machine.

20 2. Forms are used in sets of three to five and since they are made of wood in the crate factory precision work is not done and there is more or less tolerance in the outside dimensions of the forms. Also changes in atmospheric moisture affect their dimensions. Under these conditions if the side rails are set for the largest form of the set those that are smaller will be loose within the side rails. This reduces the accuracy of the locations of the nails in the work for the reason that the loose forms can move sidewise or are permitted limited rotation.

25 3. Wood forms, as they are continued in use, become somewhat loose at the corner joints and therefore more or less out of square, which does result in much unsatisfactory nailing when the forms are fed with the usual side rails as guides. Crate sections can be out of square a reasonable amount and still not be unsatisfactory for use if properly nailed.

30 40 This method or manner of gauging or aligning and stopping the form at the position desired or required with respect to the nail drivers of the chucks is inaccurate and inefficient and increasingly so as the speed of production is increased and as the day progresses due to increasing fatigue of the operator.

Such inaccuracy causes frequent displacement of the nails with the resulting necessity of a substantial amount of hand repair work to make the previously nailed parts acceptable.

35 45 The present invention relieves the operator of the mental strain and effort of aligning the form which is inaccurate at best, as the actual alignment is automatically accomplished and all that the operator need do is to advance the forms car-

rying the parts to be nailed or assembled, such as cleats, slats, strips or the like, along the work table of the machine and beneath the automatically actuated stops, there being one such stop at each side to intercept the forms and retain them in aligned position during the nailing operation, but immediately thereafter allow the form to be moved to and retained in another nailing position. With the present attachment, maximum speed of operation and production is assured along with optimum uniformity, accuracy and efficiency in the nailing operation.

In the present invention the side rails of the standard or conventional nailing machines are replaced by a roller at each lateral edge of the form and disposed directly over the clincher plates and adjustable laterally so as to avoid having nails penetrating the work in positions where they cannot be properly clinched and to avoid having cleats or slats, which rest on bridges and are parallel to the slot, improperly supported by said bridges near the points of nailing.

Among the objects of the present invention is the provision of a novel attachment which may be readily mounted onto a nailing machine and having spaced depending stops adapted to be engaged by spaced upstanding blocks or abutments on a nailing form movable relative to the stops, containing the pre-arranged cleats, slats, strips or other parts for ultimately forming the assembled section, all so constructed and arranged that these blocks or abutments upon being moved into engagement with the stops of the attachment accurately locate the position of the form and the crate or other parts disposed therein, whereby these parts will be accurately aligned with the nail drivers of the chucks and positively nailed together in their proper relation with all nails correctly located.

It is another and important object of the present invention to provide a novel means and mechanism mounted upon and operable in timed relation with the nailing drivers of a nailing machine and associated with the form in which the crate or other parts to be nailed are assembled for effecting accurate nailing and joining of these parts.

Another important feature of the present invention is the provision of a novel stop attachment for a nailing machine having depending stops automatically moved into and out of operative position in which the stops intercept and instantly and positively position the form and its contained parts to be nailed or assembled in their correct relation for the nails to be driven. The operator spends no time in locating or arranging the form in its exact position for maximum efficiency, but merely is required to quickly push or move the form forwardly; i. e. longitudinally along the work table and through the open back of the machine to its limit of movement as soon as the nail drivers and the chucks are lifted from the nail heads or work.

The invention further comprehends the provision of a novel means and mechanism for accurately locating and positioning the stops in position to intercept a form regardless of the speed of operation of the machine or the operator feeding the forms beneath the nail chucks.

Another important feature of the present invention is the manner of arranging and locating the stops so that even though the forms for the crate or other parts to be assembled may be somewhat out of square, or if some members in one plane of the crate section are non-parallel

10
15
20
25
30
35

to other members in the same plane, the stops will intercept and hold them in such manner that the nails will be driven in their proper places. This is accomplished by disposing or spacing the contact points on the forms at fixed distances from the center lines of the rows of nails which are also at fixed distances, such as the work requires, from the center lines of the cleats, slats or strips in which they are driven.

A further object of the present invention is the provision of a novel attachment for a nailing machine having stops so constructed and arranged that they may be quickly and easily adjusted to accommodate forms of varying widths and their line of travel so that no nails will impinge on the bridges of the table or protrude so close to them that they will not be properly clinched and so that any cleats or slats which rest on the bridges and are parallel to the table slot will be properly supported by said bridges near the points of nailing.

Further objects are to provide a construction of maximum simplicity, efficiency, economy and ease of assembly and operation, and such further objects, advantages and capabilities as will later more fully appear and are inherently possessed thereby.

The invention further resides in the construction, combination and arrangement of parts illustrated in the accompanying drawings, and while there is shown therein a preferred embodiment, it is to be understood that the same is susceptible of modification and change, and comprehends other details, arrangements of parts, features and constructions without departing from the spirit of the invention.

In the drawings:

Figure 1 is a view in rear elevation of the novel attachment for a nailing machine and looking in the direction of the arrows 1—1 of Fig. 2.

Fig. 2 is a view, part in side elevation and part in vertical cross section, of the novel attachment, the view being taken on the line 2—2 of Fig. 1 and in the direction of the arrows.

Fig. 3 is a fragmentary view in front elevation of the novel attachment assembled upon a nailing machine with the view merely showing approximately one-half of the machine and attachment, it being understood that the other half of the machine and attachment is similar to or a duplicate of that shown.

Fig. 4 is a fragmentary view in rear elevation of the portion of the machine and attachment of Fig. 3.

Fig. 5 is an enlarged fragmentary view in rear elevation of one of the stops of the attachment.

Fig. 6 is an enlarged view, part in side elevation and part in vertical cross section through the stop assembly and showing the stop in engagement with an abutment on the form containing the parts to be nailed.

Fig. 7 is a view in side elevation of the stop assembly with the stop elevated from an abutment or block on the form, the view being taken from the reverse side of Fig. 6 and having portions of the assembly broken away for a clearer disclosure of the operating parts.

Fig. 8 is a fragmentary view in side elevation similar to Fig. 2, but showing the stop in its elevated position as in Fig. 7.

Fig. 9 is a view in perspective of a nailed section in a nailing form, the assembled section being that of crate or one of numerous types adapted to be assembled by the present invention.

Referring more particularly to the disclosure in the drawings of the novel illustrative attachment for a nailing machine, Fig. 1 shows cross head brackets mounted upon the cross head 10 of the machine A, and hanger and support brackets mounted on the frame 11, with stops and cam rod guides or brackets mounted on the back gauge bar or in the absence of a back gauge bar, a similar bar installed for that purpose. The nailing machine A or other nailing machine on which the attachment is mounted has a feed table or work support 12 upon which an operator places a substantially rectangular nailing form 13 containing the cleats 14 and slats or strips 15 which are to be nailed together to form a crate section (Fig. 9) or any other assembly for any other purpose that can be so nailed.

The novel attachment is provided with a pair of spaced stops 16 mounted on a back gauge bar 25, which is adjustable forwardly and backwardly, or other similarly adjustable or fixed transverse member. To actuate these stops there is provided a cam bar 17 having its opposite ends 18 each supported in the lower depending end of a plate 19 joined adjacent its upper end by a connector block 21 to the lower end of a push rod 22. Each end 18 of the cam bar passes through its plate 19 and is received in an elongated slot 20 extending longitudinally in the upper end of a cam bar guide or bracket 23 having its lower end 24 slotted for receiving and mounting this guide or bracket upon the same bar or member 25 that carries stops 16.

Each stop assembly 16 (Figs. 5, 6 and 7) is provided at its rear with a supporting block or member 26 slotted at 27 to receive the back gauge bar 25 or other transverse bar or member installed on the machine for that purpose, and rigidly affixed thereto by one or more set or locking screws 28. This member 26 is rigidly secured between a pair of spaced side plates 29 forming the body of the stop and adapted to receive therebetween a forward cam roller 31 journalled in the opposite side plates 29, and a cam roller 32 having its ends journalled in and carried by upstanding or vertical extensions 33 on a pair of spaced stop levers 34. These levers are pivotally or rotatably mounted on a fulcrum pin 35 having its ends projecting through the side plates 29 and held therein by cotter pins or the like 36.

The forwardly projecting spaced ends 37 of the stop lever 34 have downward extensions 38 against which seats a contact dog 39 pivotally or rotatably mounted adjacent its upper end upon a transverse fulcrum pin 41 journalled or mounted in forward extensions 42 on the forward ends 37 of the stop levers 34. An adjustable set screw 43 carried in a spacer 43 securely mounted in an inclined position between the spaced ends 37 of the stop levers 34 provides an adjustable stop for limiting the pivotal movement of the contact dog 39. A compression spring 44 has one end seated in a recess in a spacer or block 45 anchored in and bridging the forward ends 37 of the stop levers 34, and has its other end seated in a recess in the contact dog 39 and spring-biasing the lower end of this dog forwardly or outwardly.

The stop levers 34 of each stop 16 are tilted from the full line position to the dotted line position of Fig. 6 or the full line position of Fig. 7 by means of a cam member 46 carried by and depending from the cam bar 17. The lower end 47 of this cam is relatively narrow and pro-

jects between the rollers 31 and 32 when the dog 39 is in lowered position. This narrow end then merges into an inclined surface or cam face 48 which rides over the movable cam roller 32 and thereby causes the stop levers 34 to tilt upwardly to the dotted line position of Fig. 6 and full line position of Fig. 7. When thus tilted the downward extensions 38 of these stop levers and contact dogs 39 are raised out of the path of blocks or abutments 49 disposed at spaced points or locations upon the upper surface and at the opposite sides of a nailing form 13. This form is shown as preferably of rectangular conformation with lapped joints 51 and 52 at the corners to receive the cleats 14, the slats or strips 15 or other component parts going to make up a crate section or other assembly. Any number of sets of aligned blocks or abutments 49 may be provided, depending upon the number of nailing strokes or operations required with each nailed section.

Immediately upon withdrawal of the inclined cam face 48 of the cam 46 from between the rollers 31 and 32, the stop levers are permitted to fulcrum about their pivot pin 35 and drop by gravity to the full line position of Fig. 6. Although the cam roller 31 is retained in fixed position, its pin or stub shaft 53 is preferably received in elongated, horizontally arranged slots 54 to allow for adjustment of its roller longitudinally of the slots and toward or away from the cam roller 32. Lock nuts 55 on the projecting threaded ends of the pin or stub shaft 53 rigidly hold the inner race or hub of the cam roller 31 in its adjusted position (Fig. 5).

The cam bar 17 lowers and lifts the cams 46 as the former is moved vertically. As shown in Figs. 1 to 4 and 8, such vertical movement is initiated through intermediate mechanism connected to the cam bar, upon the lowering and raising of the cross head 10 on the nailing machine by the connecting rods 10^a at the ends thereof. This intermediate mechanism includes a pair of spaced hanger brackets 56 securely mounted upon the top of the machine frame 11, and in which brackets is rotatably mounted the opposite ends of a transverse shaft 57. This shaft is provided with a hand lever 57^a for manually rotating the transverse shaft 57, when the occasion requires.

Mounted on and secured to the cross head 10 adjacent each hanger bracket 56 is a cross head bracket 58 provided with a side extension or projection 59 slidably receiving and guiding the upper end of the push rod 22. As mentioned above, each push rod is mounted at its lower end in a connector block 21, and the latter in turn is mounted upon and rigidly affixed to the upper end of the connector plate 19 carrying at its lower end an end of the transverse cam bar 17. A cushion spring 61 encompasses and is mounted on the push rod 22 intermediate its length, and in the embodiment shown the lower end of this cushion spring seats upon one or more spacers 62 which in turn seat upon one or more adjusting nuts 63 on an intermediate threaded portion of the rod. If desired, these spacers may be omitted if the push rod 22 is threaded for a length sufficient to allow for adequate adjustment of the adjusting nut or nuts 63.

A pair of tension springs 64 are secured at their upper ends to hook bolts 65 depending from a fixed support 66 on the machine, and at their lower end each spring is connected to the upper end of a connector plate 19. Each hang-

er bracket 56 and a support 66 may be combined into one bracket or fixture, if desired. Mounted on each of the opposite ends of the transverse shaft 57 carrying the hand lever 57^a is a laterally projecting arm or finger 67 which extends over the upper end of a push rod 22.

When the cross head 10 is at the top of its stroke, the stops 16 are in their lower position as shown in Figs. 1, 2, 5 and 6, with the contact dog 39 of each providing an abutment against which the opposite, aligned nailing blocks 49 on the nailing form 13 engage as this form is moved in the direction of the arrows (a) in Figs. 2, 6 and 7 and toward the stops. At such time the component parts of the attachment are in the position shown in Figs. 1, 2, 5 and 6. In fact, these parts except for the brackets 58, immediately assumed the position therein shown at the time the cross head 10 had moved up from the bottom of the previous stroke far enough for the brackets 58 thereon to break contact with the upper end of the springs 61, for as these brackets 58 moved upwardly the coil springs 64 simultaneously lifted all connected parts until the cam bar 17 reached the upper end of the slots 20 in the brackets or cam bar guides 23. The lifting of the cams 46 allows the contact dogs 39 to drop to stop position (Figs. 2 and 6) whereby the opposite, aligned blocks or abutments 49 on the nailing form 13 engage these dogs when the forms are pushed forward to the accurately located position for nailing.

When the cross head 10 descends in its nailing stroke, the projection 59 on each bracket 58 contacts its spring 61 to depress its push rod 22 and by means of the connected parts the transverse cam bar 17 is depressed or moved vertically to the bottom of the slots 20 in the brackets of cam bar guides 23. Such movement causes each cam 46 to be simultaneously forced downwardly whereby it moves its cam roller 32 rearwardly or away from cam roller 31 in Figs. 6 and 7 and causes its stop levers 34 to be tilted. Each contact dog 39 is thereby lifted sufficiently to allow the compression spring 44 to force or propel the lower end of this dog forwardly over the nailing blocks 49.

As the cross head rises, the cam bar 17 is elevated to withdraw the cam 46 from between each set of cam rollers 31 and 32, thereby permitting the stop levers 34 to drop until the contact dogs 39 thereupon rest on top of the stop blocks or abutments 49, against which they previously abutted and the nailing form 13 is then free to be moved or pushed forwardly by the operator with the abutments 49 sliding under the downward projections 38 of the stop levers 34 and the contact dogs 39 after which the projections 38 and the dogs 39 drop down onto the nailing form 13 so that the stop levers 34 are in the full line position of Fig. 6 and contact dogs 39 will intercept the succeeding set of stop blocks or abutments 49.

By contouring the stops in the manner shown in Figs. 6 and 7, if the operator wishes to pull or remove a nailing form 13 to inspect the nailing accomplished on the contained nailed section, or for any other reason, this can be readily accomplished by reason of the tapered or beveled surface 68 at the rear of the downward projection 38 of the stop levers 34, whereby retraction or withdrawal of a nailing form 13 will cause the stop blocks 49 thereon to abut or contact in succession this tapered or beveled sur-

face of the stop levers, and by reason of such contour raise the stops to allow for the partial or complete removal of the nailing form.

If the operator desires to push a nailing form 13 forwardly to any desired position without operating the machine, this may be readily accomplished by pushing upwardly on the handle 69 of the hand lever 57^a and rotating the transverse rock shaft 57 whereby the fingers 67 on the ends of this transverse shaft engage the upper ends of and push downwardly on the push rods 22. Depressing the push rods 22 in this manner lowers the transverse cam bar 17 which actuates and causes the cams 46 to tilt the stop levers 34 to the position of Fig. 7 and to lift or carry therewith the contact dogs 39 to a position above the nailing blocks 49 where they may be held by holding the hand lever in upward position until the form is pushed to the desired location.

From the above description and the disclosure in the drawings, it will be clearly apparent that the present invention comprehends a novel nailing machine attachment that is readily and easily installed on a nailing machine, and which operates automatically in synchronism with the functioning of the crosshead, nail drivers and chucks of the machine for accurately locating the form with crate parts or the like therein for the nailing operation.

It is to be understood that the nailing operation is initiated by any suitable tripping mechanism under the control of the operator, or by an electrically controlled trip mechanism which is energized for the correct period of time as the stop blocks 49 come into contact with the dogs 39, and that upon the automatic releasing of the form by the stop mechanism after a nailing stroke or operation, the form and its contained parts for fabricating a crate section or the like are moved forwardly until they are again intercepted by the stop mechanism at a succeeding nailing operation position or station. To align the form laterally on the work bed or support, the latter may be provided with an adjustable guide bar or other guiding means such as adjustable rollers B (Figs. 3 and 4). The stops and their cams being adjustable simultaneously on the back gauge and cam bar, they may be quickly adjusted to accommodate forms of any desired size within the limits of the nailing machine.

Although the present nailing attachment is referred to in connection with the assembly of sections such as form the top, bottom, sides, ends or other parts of a crate assembly, box, container or the like, it is to be understood that the invention is not limited thereto but is useful in nailing other frames or sections including frames used for the protection of articles in car loading and especially at the door of freight cars, as well as at the ends of groups of containers in the car for protection against damage by steel straps or other means for holding these containers in place. The attachment is also adapted for use in nailing together the skids and the wood boards in a platen and for other frames or forms and purposes which will be readily apparent to those skilled in the art.

The disposition, spacing and number of sets of the blocks or abutments 49 depend upon and may be varied in accordance with the location and spacing of the rows of nails to be driven. The arrangement shown in Fig. 9 is but illustrative and shows three sets of spaced stops or abutments

49 and three rows of nails driven in staggered arrangement by nail drivers disposed in similarly staggered relation. The amount of stagger may be varied, if desired, by adjustment of the rails to which the nail chucks are attached.

Having thus disclosed the invention, I claim:

1. In combination with a nailing machine having nailing chucks and a work table over which the parts to be nailed are moved and positioned beneath the nailing chucks, a form for receiving and maintaining the parts in their proper relation for nailing and having a plurality of upstanding abutments thereon and at the opposite sides of the form, an attachment mounted on the nailing machine and movable with the cross head of the nailing machine, a transverse member mounted on the machine and spaced stops adjustably mounted on said member and depending over the work table for engaging the abutments on the form and thereby intercepting and retaining the form in accurately located position beneath the chucks during each of the successive nailing operations or strokes of the machine.

2. In combination with a nailing machine, means for accurately aligning and locating upon the work table of the machine and beneath its nailing chucks a slideable nailing form containing the cleats and slats to be nailed and joined into a section forming a panel or other part of a crate, including spaced projections provided on the opposite sides of the form, a supporting bar mounted on the machine above the work table, and spaced depending stops adjustably mounted on the machine and each stop adapted to engage and intercept a projection on the form as the latter is moved over the table for accurately locating the form beneath the chucks for the one or more strokes of the machine or nailing operations.

3. In combination with a nailing machine having nailing chucks and a work table spaced therefrom and adapted to receive therebetween cleats and slats for the assembly of a wooden section, a form for receiving and retaining these cleats and slats in proper position for assembly, and inter-engaging means on the form and machine for intercepting the form as it is moved over the work table and beneath the nailing chucks for accurately locating and retaining the cleats and slats to be nailed beneath the chucks, said means including upstanding projections on the opposite sides of the form, a supporting bar mounted on the machine and disposed transversely of and above the work table, and spaced stops adjustably mounted on said bar and depending therefrom for engaging a projection at the opposite sides of the form to intercept and align this form and its cleats and slats for nailing.

4. In combination with a nailing machine having a work table adapted to receive a nailing form and contained parts to be nailed to form a wooden section of a crate, container or the like with the forms and contained parts slid along the table to successive nailing stations, nailing chucks and a reciprocating cross head located above the work table, spaced projections on the form, a supporting bar mounted above the work table and depending stop members carried by the supporting bar and actuated by movement of the cross head and engaged by aligned projections on the form to locate and retain the form and its contained parts in nailing position for each stroke of the crosshead.

5. In combination with a nailing machine hav-

ing a work table adapted to receive a nailing form and parts to be nailed to fabricate a section of a crate, container or the like, nailing chucks and a reciprocating cross head located above the work table, abutments upon the opposite sides of the form and spaced apart along the form in conformity with the predetermined spacing of the rows of nails driven during successive nailing strokes of the machine, a supporting bar mounted on the machine and extending across the work table, and depending stop members adjustably mounted on said bar and actuated by movement of the cross head and so spaced and arranged as to successively engage an abutment on each of the opposite sides and thereby intercept the form as it is moved along the work table and retain it and the contained parts aligned during each successive nailing stroke or operation of the machine.

6. In combination with a nailing machine having a support for receiving parts to be nailed to fabricate a panel or other section of a crate, container or the like, a cross head and nailing mechanism for joining the parts, and mechanism for accurately locating said parts in predetermined positions beneath the cross head for successive nailing strokes of the machine, said mechanism including spaced abutments at the opposite sides of the panel or other section and moving along the support with the parts forming the panel or other section, a supporting member mounted on the machine and disposed above and extending across the work table, and stop members carried by the supporting member in spaced relation across the machine and adapted to be moved into the path of said abutments for locating and retaining the parts in predetermined and properly aligned positions during nailing.

7. In combination with a nailing machine having a work table adapted to receive a nailing form and parts to be nailed to fabricate a section of a crate, container or the like, nailing chucks and a reciprocating cross head located above the work table, abutments upon the laterally spaced and longitudinally extending sides of the form and spaced apart in conformity with the predetermined spacing of the rows of nails driven during the successive nailing strokes of the machine, a supporting member mounted on the machine and extending across the work table, and pivotally mounted stop members carried by said supporting member in spaced relation and each adapted to engage an abutment at the laterally spaced sides of the form to thereby intercept the form as it is moved along the work table and retain it and the contained parts during each successive nailing stroke of the machine, and depending cam-actuated means for elevating each stop member to release the form upon completion of each nailing stroke for movement to a succeeding nailing position.

8. In combination with a nailing machine having a work support and a form for receiving parts to be nailed to fabricate a panel of a crate, container or the like, nail drivers for joining the parts, and mechanism for accurately locating said parts in predetermined positions beneath the nail drivers for successive nailing strokes of the machine, said mechanism including spaced abutments at the opposite sides of the form and moving along the support with the parts forming the panel, a member mounted on the machine and extending transverse of the support and cam-actuated stop members adjustably mounted on

said member in spaced relation and adapted to intercept the form as it is moved along the support and retain the form and the contained parts during successive nailing strokes of the machine.

9. In combination with a nailing machine having a work table adapted to receive a nailing form and contained parts to be nailed to form a wooden section of a crate, container or the like with the forms and contained parts slid along the table to successive nailing stations, nailing chucks and a reciprocating cross head located above the work table, laterally spaced roller guides at the opposite sides of the work table, spaced projections on the form, a supporting bar mounted above the work table and depending stop members carried by the supporting bar and actuated by movement of the cross head and engaged by aligned projections on the form to locate and retain the form and its contained parts in nailing position for each stroke of the cross head.

10. In combination with a nailing machine having nailing chucks and a work table spaced

therefrom and adapted to receive therebetween cleats and slats for the assembly of a nailed section, a form for receiving and retaining these cleats and slats in proper position for assembly, 5 roller guides at the opposite sides of and longitudinally of the path of travel of the form, interengaging means on the opposite sides of the form and on the machine for intercepting and retaining aligned the form as it is moved over 10 the work table and beneath the nailing chucks for accurately locating and retaining the crate parts beneath the chucks, and cam-actuated means for releasing said interengaging means to permit movement of the form and its contained parts to a succeeding nailing station.

JENNESS B. FREAR.
